ABSTRACT: A thermomagnetic flasher having a main pull wire controlled armature to make and break a first contact pair, an auxiliary armature extending from the main armature to make and break a second contact pair, and an electromagnetically-controlled armature to make and break a third contact pair. During heating of the pull wire, the contact pairs close in second-first-third order, and during cooling of the pull wire, the contact pairs open in first-second-third order. The second and third contact pairs control a load current path paralleling the path controlled by the first contact pair. In the foregoing cycle, during heating of the pull wire, the path through the first contact pair closes first to energize the load, and the path through the second and third contact pairs closes second. During cooling of the pull wire, the path through the first contact pair opens first, but the load is still energized by the path through the second and third contact pairs, which opens second.

LOAD INDEPENDENT THERMO-MAGNETIC FLASHER

The present invention relates to a flasher unit employing thermally and magnetically generated forces in its operation. More specifically, a pull wire is employed to control a main armature and an auxiliary armature attached thereto, while an electromagnet is employed to control a third armature.

The flasher unit embodying the present invention has numerous advantages. This unit can replace both shunt and series-type flashers, is capable of directional and emergency signalling, and can provide a positive pilot indication over a wide range of loads. The ON time is almost exclusively a function of the cooling rate of the pull wire, and the speed (rate) adjustment is independent of the ratio adjustment. Also, contact breaking speed is sufficiently high to enable the use of relatively low-cost contact material.

The invention may be better understood by reference to the accompanying drawing, of which:

FIG. 1 is a diagram of the preferred embodiment of the flasher unit showing the electrical and mechanical features thereof, and the manner in which the flasher unit is connected to external circuitry.

Referring to FIG. 1, the flasher unit 10 comprises a main armature 12 which is attached to a rigid support member 14 by a leaf spring 16. Main armature 12 has an extension 18 to which one end of pull wire 20 is mechanically and electrically connected. The other end of pull wire 20 is secured by an insulating glass bead 22 set in a mechanical support 24. The pull wire 20 is connected in series with a ballast resistor 26, one terminal of which is connected to fixed contact 28, which is in a cooperative make-and-break relationship with movable contact 30 mounted on main armature 12. Pull wire 20 maintains contacts 28 and 30 normally open against the bias of leaf spring 16.

Mechanically and electrically connected to main armature 12 is a flexible auxiliary armature 32 which is slaved to the motion of main armature 12 and serves to control the making and breaking of fixed contact 34 and movable contact 36 mounted on the auxiliary armature 32. An essential feature of the present invention is that the gap between the normally open contacts 28 and 30 must be greater than the gap between the normally open contacts 34 and 36, so that the latter pair of contacts will close first upon heating of the pull wire 20.

A third armature 38 is mounted to fixed support 40 by means of a leaf spring 42, which biases the armature 38 so that the fixed and movable contacts, 44 and 46 respectively, are normally open. Contacts 44 and 46 close when there is a sufficiently strong magnetic force exerted on armature 38 by coil 48 and magnetic core 50, which, like core 52, is U-shaped. Cores 50 and 52 may also be integrally formed in the shape of an "I" laid on its side (as it would appear in the drawing). Coil 48 and magnetic core 52 serve to exert an attracting electromagnetic force on main armature 12 and auxiliary armature 32 during a portion of the operating cycle of the flasher unit. Fixed contact 44 is connected to fixed contact 34, and movable contact 46 is connected through armature 38 to fixed contact 28. The coil 48 is connected between fixed contact 28 and the load terminal 54. Battery terminal 56 is connected through mechanical mount 14, leaf spring 16, and main armature 12 to movable contact 30; through the mount 14, spring 16 and the auxiliary armature 32 to movable contact 36; and through the mount 14, spring 16, main armature 12, pull wire 20, and ballast resistor 26 to fixed contact 28.

The external circuitry to which the flasher unit 10 is connected consists of battery B, which is connected to battery terminal 56, and load L which is connectable through switch S to load terminal 54.

The operation of the flasher unit is as follows:

When switch S is closed, a small current will flow from battery B through battery contact 56, spring 16, main armature 12, its extension 18, pull wire 20, ballast resistor 26, coil 48 and load terminal 54 through switch S and load L. Where load L is a lamp load, this current is sufficiently small to prevent the

lamps from becoming incandescent. As this current passes through pull wire 20, thereby causing same to heat and expand, main armature 12 and auxiliary armature 32 begin to move downward. As this motion progresses, contacts 34 and 36 close first. However, this event has no immediate effect, since contacts 44 and 46 are still open, thus holding open the portion of the circuit from contact 34 to ground. After contacts 34 and 36 have closed, main armature 12 continues to travel downward until contacts 28 and 30 close, thus energizing the load L. Current now flows from battery B through terminal 56, spring 16, main armature 12, contacts 28 and 30, through coil 48, terminal 54, switch S and load L to ground, thereby creating magnetic fields in cores 50 and 52. The field generated in core 52 exerts a magnetic attraction on main armature 12 to aid the force of leaf spring 16 in maintaining contacts 28 and 30 closed. The magnetic field in core 50 attracts armature 38, thereby causing contacts 44 and 46 to close substantially simultaneously with the closing of contacts 28 and 30. The portion of the load current path comprising main armature 12 and contacts 28 and 30 connected between leaf spring 16 and the high side of coil 48 is now paralleled by auxiliary armature 32, contacts 34 and 36, contacts 44 and 46, and armature 38 connected between the same points. Heating current is now shunted from pull wire 20, which begins to cool. As pull wire 20 contracts, it exerts sufficient force on the main armature 12 to overcome the magnetic attraction of the field generated in core 52, thus causing contacts 28 and 30 to break, but load current continues to flow through auxiliary armature 32, contacts 34 and 36, contacts 44 and 46, armature 38 and coil 48. Since the magnetic field of coil 48 is thus maintained, there is no inductively generated voltage to cause arcing across contacts 28 and 30 when they open. As the main armature 12 moves upward, it engages auxiliary armature 32 and thereby causes contacts 34 and 36 to open. The breaking speed of contacts 34 and 36 is relatively high due to the camming action of main armature 12 on auxiliary armature 32. Also, at the time of the separation of contacts 34 and 36, the field in core 52 collapses as a result of the cessation of flow of load current through coil 48, thus eliminating the magnetic forces exerted on armatures 12 and 32 and further enhancing the breaking speed of contacts 34 and 36. Substantially simultaneously with the opening of contacts 34 and 36, contacts 44 and 46 also open as a result of the collapse of the magnetic field which serves to attract armature 38 to core 50. Heating current again begins to flow through pull wire 20 as described earlier, and the foregoing cycle will continue to repeat itself as long as switch S is closed.

The advantages of the present invention, as well as certain changes and modifications to the disclosed embodiment thereof, will be readily apparent to those skilled in the art. It is the applicant's intention to cover all those changes and modifications which could be made to the embodiment of the invention herein chosen for the purposes of the disclosure without departing from the spirit and scope of the invention.

I claim:

1. A two-terminal thermomagnetic flasher unit comprising:
  1. first and second terminals;
  2. first circuit-controlling means operative to close and open a first load current path; and
  3. second circuit-controlling means operative in cooperation with said first circuit control means to close and open a second load current path which is partially in parallel and partially coincident with said first load current path between said first and second terminals, said first and second circuit-controlling means being jointly operative, when a source of direct-current power and a load are connected in series between said first and second terminals, sequentially to close said first load current path, to close said second load current path, to open said first load current path, and to open said second load current path during each flashing cycle.
2. A thermomagnetic flasher unit according to claim 1 wherein:
  1. said first circuit-controlling means comprises

- a. a main armature having a first movable contact mounted thereon in cooperative make-and-break relationship with a first fixed contact;
  - b. mounting means for said main armature;
  - c. a pull wire connected to said main armature for controlling the position thereof; and
  - d. electromagnetic means operative when energized to exert an attractive magnetic force upon said armature.
3. A thermomagnetic flasher unit according to claim 2 wherein a ballast resistor is connected between said pull wire and said first fixed contact.
4. A thermomagnetic flasher unit according to claim 2 wherein said mounting means includes a leaf spring operative to bias said first contacts toward a closed position.
5. A thermomagnetic flasher unit according to claim 2 wherein:
- 1. said second circuit-controlling means comprises
  - a. a flexible auxiliary armature attached to said main armature and having a second moveable contact mounted thereon in cooperative make-and-break relationship with a second fixed contact, the gap between said first contacts being greater than the gap between said second contacts; and
  - b. relay means including a coil in common with said electromagnetic means and operative when energized to close a current path between said second fixed contact and said first terminal.
6. A thermomagnetic flasher unit according to claim 5 wherein said coil is connected between said first fixed contact and said first terminal, and disposed about at least one magnetizable core member.
7. A thermomagnetic flasher unit according to claim 6 wherein said coil is disposed about first and second U-shaped magnetizable cores, said first core being operatively associated with said main and auxiliary armatures and said second core being an element of said relay means.
8. A thermomagnetic flasher unit according to claim 5 wherein said relay means further comprises an armature hav-

5 ing a third movable contact mounted thereon in cooperative make-and-break relationship with a third fixed contact, said relay means being operative when energized to close a path between said second fixed contact through said coil to said first terminal.

9. A thermomagnetic flasher unit comprising:

- 1. a main armature, a movable contact mounted thereon, and a fixed contact in cooperative make-and-break relationship with said movable contact;
- 2. mounting means for said main armature connected to a first terminal of said flasher unit and operative to urge said first contacts to a closed position;
- 3. a pull wire attached at one end to said main armature and connected to said fixed contact, said pull wire, when cool, maintaining said first contacts normally open;
- 4. means for fixedly securing the other end of said pull wire;
- 5. a ballast resistor connected between said pull wire and said first fixed contact;
- 6. an auxiliary armature connected to said main armature, a movable contact mounted thereon and a fixed contact in cooperative make-and-break relationship with said movable contact, said auxiliary armature contacts being set with a smaller gap than said main armature contacts;
- 7. an electromagnetic relay including a coil, first and second magnetizable cores, an armature controlled by the magnetic forces exerted by said second core in response to current through said coil, a movable contact mounted on said armature, and a fixed contact in cooperative make-and-break relationship with said movable contact, one terminal of said coil being directly connected to said first fixed contact, said relay being operative to make and break a current path between said one terminal of said coil and said second fixed contact, the other terminal of said coil being connected to a second terminal of said flasher unit, and said second core being operative in response to the current flowing through said coil to exert magnetic forces upon said main and auxiliary armatures.
